(57) **CLAIM**

The ornamental design for an oven mitt, as shown and described.

DESCRIPTION

FIG. 1 is a front view of an oven mitt, according to my new design;

FIG. 2 is a back view thereof;

FIG. 3 is a left side view thereof;

FIG. 4 is a right side view thereof;

FIG. 5 is a top view thereof; and,

FIG. 6 is a bottom view thereof.

The dash dot lines depict portions of the oven mitt that form no part of the claimed design.

1 Claim, 5 Drawing Sheets
